UNITED STATES PATENT OFFICE

2,223,970

ELECTRIC INDUCTION HEATING
APPARATUSNuman R. Stansel, Schenectady, N. Y., assignor to
General Electric Company, a corporation of New
York

Application April 29, 1939, Serial No. 270,818

2 Claims. (Cl. 219—13)

My invention relates to electric induction heating apparatus, more particularly to high frequency induction heating apparatus, and has for its object simple and reliable apparatus for heating a portion of an object.

My invention is especially useful in surface hardening operations wherein it is desired to harden portions only of the surfaces of metal objects. Uniformly shaped objects for example, shafts, may be conveniently heated for surface hardening by high frequency coreless inductive heating means, this heating means being characterized by the fact that the generation of heat is confined to a thin outer layer which may be heated to a hardening temperature without heating the interior of the article to that temperature. However, this method heats the entire surface of the article whereas in some articles, such as steel rails for railroads, it is desirable to heat the top wearing surface only.

In accordance with my invention, I provide a shield for the body to be heated which shield is made of high electrical conductivity material, preferably copper, and is arranged to surround the body except for the portion or surface of the body which is to be heated. This shield is of such thickness as to substantially prevent interlinkage of the high frequency magnetic flux with all portions of the body covered by it.

For a more complete understanding of my invention, reference should be had to the accompanying drawing in which Fig. 1 is an elevation view of a high frequency induction heater for railroad rails embodying my invention, while Fig. 2 is an enlarged view in section taken along the line 2—2 of Fig. 1 looking in the direction of the arrows.

Referring to the drawing, I have shown my invention in one form as applied to the heating of the treads on the ends of railway rails for the purpose of hardening the treads. This hardening is desirable to prevent the excessive wear at the ends of the rails occasioned by the joint between the rails.

The heating apparatus comprises a helical high frequency heating or magnetic flux inducing primary winding 10 which is large enough to provide for the insertion of the ends of two rails 11 and 12 in aligned and abutting relation in the winding as shown in Fig. 1. The rails and the heating winding are mounted on suitable supports 13 and 14. As shown, the winding is mounted on a bar 15 made of electrically insulating material whose ends are secured to the supports 13 and 14, the turns of the winding at

the top being in closely spaced relation with the top or tread portion 18 of the rail which is to be heated. The conductor of the winding 10 is made from a tube in the conventional manner so that cooling water may be circulated through it. It is supplied by means of conductors 16 and 17 with a current of suitable high frequency, preferably on the order of two thousand cycles.

Unless some means were provided to prevent it, the entire surfaces of the rails at their two ends inserted in the winding would be heated. It is desired however to heat only the tread, i. e., the top portion 18 at the ends of the two rails. For the purpose of shielding the remaining surfaces of the rails from interlinkage by the electromagnetic flux set up by the winding 10, I have provided a shield 19 which surrounds the rails except for the tread surface 18 and thereby prevents the generation of heat in all portions except the treads. This shield is preferably made of a material having a good electrical conductivity, such as copper. As shown, it loosely conforms with the shape of the rails and is provided with a top opening 20, exposing the tread 18, and strengthening ribs 21. It extends between the supports 13 and 14 and is supported at each end on the supports. It will be noted that the shield because of the top opening 20 is discontinuous electrically in a circumferential direction throughout its length. Also as shown, the shield projects from each end of the winding 10 so as to prevent the magnetic flux from passing through the air around the end of the shield into the rail.

The shield is preferably made of imperforate sheet metal having a uniform thickness, which thickness in a direction radial with respect to the coil 10 would in practice be about $\frac{1}{4}$ inch with a frequency of approximately two thousand cycles. For the most effective shielding the thickness must be not less than three times the equivalent depth of penetration of uniform magnetization as expressed by Steinmetz (Theory and Calculation of Transient Electrical Phenomena and Oscillations, 3rd edition, 1920, p. 371) as follows:

$$p = \frac{3570\sqrt{\rho}}{f\sqrt{\mu}}$$

wherein p equals equivalent depth of penetration in centimeters, ρ equals resistivity of the material of the shield in ohms cm.³, f equals frequency, 60 cycles per second, μ equals permeability of the metal of the shield equals 1 for copper.

A shield having a thickness equal to four times the equivalent depth of penetration as given by the above formula, absorbs about 98 per cent of

the magnetic flux tending to interlink with the rail, except for the exposed tread portion 18, so that practically no heat would be generated in the shielded portion of the rail. In the hardening 5 application disclosed a small amount of heat generation in the shielded portion of the rail is not detrimental.

- It will be understood that the apparatus will be designed to heat the tread surface 18 quickly to 10 a desired hardening temperature of 900° C. or higher after the insertion of the rails or the application of power to the winding 10, perhaps in a period of a few seconds. This quick heating is required to effect the heating of a surface layer at 15 the tread, such as $\frac{1}{8}$ to $\frac{1}{16}$ of an inch in thickness, to the hardening temperature so quickly that the inner portion of the rail is not appreciably heated by conduction of heat from the surface. The rails are then removed and quenched immediately.
- 20 The frequency used is selected as a compromise between the thickness of the shield, the exciting current, the voltage of the supply source, and cost of the apparatus, there being considerable leeway in connection with the required heating effect.

While I have shown a particular embodiment of my invention, it will be understood, of course, that I do not wish to be limited thereto, since many modifications may be made and I, therefore, contemplate by the appended claims to cover any such modifications as fall within the true spirit and scope of my invention.

What I claim as new and desire to secure by Letters Patent of the United States is:

- 35 1. Apparatus for heating a predetermined surface portion to a predetermined depth of a body made of magnetic material, comprising a primary induction heating winding of such size that the body to be heated may be inserted therein so as to be surrounded by said winding, a magnetic shield made of copper inside said winding arranged to surround the body except for said surface portion to be heated, said shield being discontinuous electrically in a circumferential di-

rection throughout substantially its entire length and projecting from each end of said winding so as to exclude substantially the magnetic flux produced by said winding from the surface of the body inserted in said winding except said predetermined surface; and electric connections for supplying high frequency current to said winding whereby a magnetic flux is caused to interlink with said surface portion and thereby heat said surface portion to a predetermined temperature, 10 said shield having a thickness in a direction radial of said winding sufficient to exclude substantially all magnetic flux set up by said winding from all other surface portions of the body.

2. A high frequency induction heating apparatus for heating the treads of steel rails and the like to hardening temperatures, comprising a primary induction heating winding of such size that the rail to be heated may be inserted loosely 15 therein so as to be surrounded by said winding and with the tread to be heated closely adjacent the turns of said winding, a magnetic shield made of copper inside said winding arranged to surround the rail except for the tread to be heated, said shield having substantially the cross sectional shape of the rail to be heated and being discontinuous electrically in a circumferential direction but structurally continuous axially throughout substantially its entire length and projecting from each end of said winding so as 20 to exclude substantially the magnetic flux produced by said winding from the surface of the rail inserted in said winding except the tread to be heated, and electric connections for supplying a high frequency current to said winding whereby 25 a magnetic flux is caused to interlink with the tread and thereby heat the tread to a predetermined temperature, said shield having a thickness in a direction radial of said winding sufficient to exclude substantially all magnetic flux 30 set up by said winding from all other surface portions of the rail enclosed by said winding.

NUMAN R. STANSEL.
